Czechoslovakia

Application November 16, 1936, Serial No. 111,169
In Germany November 23, 1935

10 Claims. (Cl. 122—31)

The invention relates to the production of high pressure steam by blowing superheated steam into the water space of a boiler drum. This system of steam production enables the boiler to be operated with very high concentration of salts in the boiler water, particularly when effecting positive circulation of the steam serving as heat carrier. The object of the invention is to ensure and to improve the purity of the steam produced and to enable even more concentrated boiler water to be employed.

According to this invention in order to attain this object the feed water is fed into the boiler drum in the neighbourhood of the individual hot steam injectors or the plurality of the injectors in such a way that the concentration of salts in the boiler water in the region of the outlet opening of each injector is less than in the remaining water space of the boiler drum and the most intensive vaporisation takes place in this region of lower concentration of salts in the boiler water.

The accompanying drawing illustrates by way of example three embodiments of boiler plants according to the invention. The same reference numerals are used in each of the figures to indicate like parts of apparatus.

Referring to the drawing, 1 indicates the boiler drum for the production of steam, 2 the inlet pipe for the hot steam serving as heat carrier, 3 the injectors from which the hot steam is blown into the water space of the boiler 1, preferably in a downward direction, and 4 the inlet pipe for the fresh feed water,

In the embodiment illustrated in Fig. 1 the feed water is introduced from the distributing pipe 4 through separate injectors 5 into the water space of the boiler 1. One feed water injector 5 is for example disposed close to each steam injector 3. These injectors 5 are fan shaped and inclined slightly downwards to the horizontal, each being directed towards the region in front of the outlet opening of one steam injector 3. The feed water accordingly flows in a wide jet in front of the outlet opening of each steam nozzle 3 and fills up the region in front thereof. The hot steam discharging from the injectors 3 consequently meets fresh feed water, before coming into contact with the boiler water, which is considerably concentrated in salts etc., and the first transfer of heat, i. e., the most intensive vaporisation, takes place within this region of lower concentration of the water.

With this arrangement of the distributing pipe 4 and the feed water injectors 5 the movement of

the water contained in the boiler drum is also favourably promoted by the feed water flowing out of the injectors 5.

In the embodiment illustrated in Fig. 2 a feed water inlet or injector 6 is disposed directly in front of the outlet opening of each steam injector 3. These feed water injectors 6, which, in order to control the distribution of the feed water to the individual injectors, are formed of throttling discs, are turned towards the steam injectors 3 and constructed in the form of open funnels 7, which widen out to the cross section of the outlet openings of the steam injectors 3 or wider. A baffle plate 8 is disposed in each of these funnel-shaped injectors 7 in such a way that jets of feed water cannot be injected into the interior of the steam injectors 3.

In the embodiment illustrated in Fig. 3 the feed water outlets are constructed in the form of annular nozzles or injectors 9, which are disposed concentrically around the steam injectors 3 and in the same direction as the same. These feed water injectors 9 are tapered conically at the delivery end, so as to prevent the annular jets of feed water from spreading out. Conical guide rings 10 are likewise disposed on the inner edge of the feed water injectors 9 in order to contract the feed water jet in the form of a cone. These guide rings 10 may also serve the purpose of preventing the hot steam currents from spreading on their discharge from the steam injectors 3. Baffle plates 11 are disposed at a short distance in front of the outlet openings of the steam injectors 3 and the feed water injectors 9. As a result thereof the hot steam jets must cross the annular feed water jets, before they reach the highly concentrated boiler water.

The feed water is introduced into the injectors 9 from the distributing pipe 4 through channels 12, which surround the steam injectors 3 along the greater part of their length. The feed water is conveyed from the distributing pipe 4 into the upper end of the annular channels 12, so that a constant stream of fresh feed water always flows along the outer surface of the steam injectors 3.

What I claim is:

1. A boiler plant for production of high pressure steam comprising a boiler drum with steam and water spaces; means for blowing superheated steam into said water space comprising a steam main and a plurality of steam nozzles connected to said main and opening freely into the water space, means for supplying feed water comprising a feed-water main and a plurality of feed water nozzles connected to said feed water main, the

outlet openings of said steam nozzles and said feed water nozzles being directed toward one another in such manner that the feed water is directly conveyed toward the outlet of said steam nozzles and that the steam leaving said steam nozzles is directly carried into said fresh feed water stream and must cross the same before coming in contact with the drum water.

2. A boiler plant as set forth in claim 1 in which said means for supplying feed water consist of fan shaped nozzles the openings of which are directed towards the outlet openings of said hot steam nozzles, the arrangement being such, that a stream of fresh feed water flows in the form of a wide jet in front of each hot steam nozzle.

3. A boiler plant as set forth in claim 1 in which said means for supplying feed water consist of feed water inlet nozzles in the form of an open funnel, each of said funnel-shaped nozzles being widened at least to the cross section of the outlet opening of the corresponding hot steam nozzle.

4. A boiler plant as set forth in claim 1 in which said means for supplying feed water consist of feed water inlet nozzles in the form of an open funnel widening at least to the cross section of the outlet opening of the corresponding hot steam nozzle, and in which a baffle plate is arranged in each of said funnel shaped feed water nozzles in such a manner that the jets of feed water cannot enter the said hot steam nozzles.

5. A boiler plant as set forth in claim 1 in which said means for supplying feed water consist of nozzles disposed concentrically around the said hot steam nozzles in the same direction as the latter in such a manner that the hot steam jets discharging into the boiler are surrounded by streams of fresh feed water.

6. A boiler plant as set forth in claim 1 in which said hot steam nozzles are tapered conically and said means for supplying feed water com-

prise nozzles disposed concentrically around said conically tapered hot steam nozzles.

7. A boiler plant as set forth in claim 1 in which said hot steam nozzles are tapered conically, said means for supplying feed water comprise nozzles disposed concentrically around said conically tapered hot steam nozzles, and baffle plates are arranged in front of the outlet openings of the said hot steam nozzles and said water supplying nozzles.

8. A boiler plant as set forth in claim 1, in which said means for supplying feed water comprise nozzles, the outlet openings of said nozzles being similar to the outlet opening of the superheated steam nozzle and being coaxially arranged to said steam nozzles in such a manner, that the superheated steam jets discharged from the nozzles into the boiler contact a body of fresh feed water before coming into contact with the boiler water.

9. A boiler plant as set forth in claim 1, in which said means for supplying feed water comprise nozzles of the shape of an open funnel and are arranged coaxially to the steam nozzles directly in front of the outlet openings of same, each of said funnel-shaped nozzles being widened out to at least the cross section of the outlet opening of the coordinate steam nozzle.

10. A boiler plant as set forth in claim 1, in which said means for supplying feed water comprise nozzles of the shape of an open funnel and are arranged coaxially to the steam nozzles directly in front of the outlet openings of same, each of said funnel shaped nozzles being widened out to at least the cross-section of the outlet opening of the coordinate steam nozzle, a baffle plate being arranged in each of said funnel shaped feed water nozzles in such manner that the jets of feed water are prevented from entering said superheater steam nozzles.
